WATER TANK FOR CONCRETE MIXERS

Lion Gardiner, Columbus, Ohio, assignor to The
Jaeger Machine Company, Columbus, Ohio, a
corporation of Ohio

Application December 24, 1931, Serial No. 583,027

6 Claims. (Cl. 221—95)

This invention relates to tanks for supplying water to concrete mixing drums.

The object of the invention is to provide an improved tank or reservoir having two water containing chambers, one of which receives the water for supplying the dry ingredients of several batches of the concrete while the other receives the water for washing out the mixing drum after the day's work has been completed or before, if desired. A further object is to provide an improved construction whereby a measured quantity of water, according to specifications for the slump, can be discharged into the mixing drum containing the ingredients and unauthorized additions to the main quantity in the tank made detectable. A further object is to prevent supplying of water to the tank (and the mixing drum) when the water charging opening to the tank is opened. Other objects will appear from the disclosure herein.

The invention is embodied in the example herein shown and described, the features of novelty being finally claimed.

In the accompanying drawing—

25 Figure 1 is a view in side elevation of the tank with parts broken out to illustrate details.

Fig. 2 is a top plan view of the tank showing parts in broken lines.

30 Fig. 3 is a sectional detail showing the construction of the siphoning or discharge pipe.

In the views 5 designates the tank which is generally of parallel piped form, said tank having the main supplying chamber 6 and the wash water chamber 7.

35 The bottom of the main chamber 6 is provided with an upwardly extending housing 4 containing an outlet casing 8 in which is seated a perforated valve-like tapered plug 9 to one end of which a so-called siphon pipe 10 is connected to extend 40 at right angles to the axis of the plug and into the chamber so that the pipe 10 can be elevated and depressed within the tank on the axis of the plug to the extent desired to effect the withdrawal of a predetermined quantity of water. The 45 position of the open upper end of the pipe 10 below the level of the water determines the quantity that can be withdrawn. Connected with the opposite end of the plug 9, which is external to the wall of the chamber, as seen in Fig. 3, is a 50 bent arm 11 by means of which the plug can be rocked to raise or lower the siphon pipe. The arm 11 works over a fixed arcuate bar 14 having a lateral flange 15 against the lower side of which the adjacent end of the pivoted handle 55 can be pinched by a clamp device at 11^a to lock

the arm 11 in the position to which placed. The arm 14 can be provided with a scale indicating gallons or other units of water so that the arm can be moved from point to point and secured to depress the siphon pipe to draw successively 60 the units of water when and as required for the several batches of concrete.

The plug casing 8 communicates with a valve casing 16 containing a valve controlled by a hand wheel 17; and the casing 16 has a pipe 18 leading 65 to the mixing drum (not shown).

The wash water chamber 7 has connected with its bottom a discharge pipe 19 that communicates with the pipe 18; but interposed in said pipe 18 is a valve casing 20 containing a valve 70 that is operated by a spring held handle 20^a holding the valve normally closed so that water from the wash water chamber 7 can be conducted to the pipe 18 and the concrete mixing drum when desired.

75 The top of the tank or reservoir 5 is provided with an opening through which water is supplied to both chambers, the chamber 7 being filled by overflow from chamber 6, said opening being closable by a cover 21 pivoted to a bar 22 that is pivoted at 22^a on the top of the tank. Hingedly connected with said bar 22 is one end of a link 23, the other end of said link being hinged to one arm of a bell crank lever 24 pivoted at the corner of the tank.

80 The other arm of the bell crank lever 24 has hinged to it a rod 25 that extends downward adjacent the end of the tank through a fixed perforated guiding bracket 26, said rod 25 provided at its lower end with a foot 27. A loose removable link 22^b can be employed to hold the cover 21 down until it is to be operated. By pulling down on the rod 25 the cover 21 can be opened to permit the introduction of a hose to fill the water chambers 6 and 7. The position of said foot 27 85 is such that, when the hand wheel 17 is in the position occupied with the valve open, the rod cannot be depressed, hence it is only when the valve is closed that water can be supplied as stated to the chamber 6 through the opening at 100 the top.

A rod 30 having float member 31 at its lower end is hung in a bearing, as at 32, at the top of the chamber 6 to swing in said chamber, said rod projecting externally beyond the end of the tank and having a short downward projection or pointer such as shown at 30^a parallel to the internal rod so that the angular position of the latter will indicate the depth or quantity of water or absence of water in said chamber. An arcuate 105

scale not shown but of ordinary and obvious construction can be affixed to the tank opposite said pointer to indicate the quantity or units of quantity of water present in the chamber.

- 5 A rod 33 similar to the rod 30 and with its described appurtenances is shown installed in the wash water chamber 7 to indicate the quantity of water in said chamber 7 with an external pointer 33^a and indicator as described.
- 10 The forms of the parts can be changed without departing from the gist of the invention.

What I claim is:

1. A tank for supplying water to a concrete mixer provided with a discharge outlet to the concrete mixer, a valve for controlling said outlet, a charging opening, a movable closure for said charging opening, means for operating said closure to expose said opening, said means being inoperable when said outlet valve is in open position.
- 20 2. A tank for supplying water to a concrete mixer, provided with a discharge outlet to the concrete mixer, a valve for controlling said outlet, a handle for moving said valve, a charging opening, a movable closure for said opening and means for operating the same to expose said opening, said valve handle serving as a stop to prevent the exposure of said opening when the discharge valve is in open position.
- 30 3. A tank for supplying water to a concrete mixer, said tank also provided with two chambers and an outlet from each chamber to the concrete mixer, a valve and a handle thereon for controlling each of said outlet, a water charging opening in the tank for supplying both of said chambers, a movable closure for said water charging opening, and means for operating said closure to expose said opening, one of said handles preventing the operation of said closure operating means to expose said opening when its valve is in open position.

4. A tank for supplying water to a concrete mixer, said tank also provided with two chambers and an outlet from each chamber to the concrete mixer, said outlets having a common discharge, a valve and a handle for controlling each of said outlets, a water charging opening in the tank for supplying both of said chambers, a movable closure for said water charging opening, and means for operating said closure to expose said opening, one of said handles, when in the position of its valve open, constituting a stop to prevent the operation of the closure to expose said charging opening.

5. A tank for supplying water to a concrete mixer, provided with two chambers, and an outlet from each chamber to the concrete mixer, a valve and a handle for controlling each of said outlets, a water charging opening in the tank for supplying both of said chambers, a movable closure for said water charging opening, means for operating said closure to expose said opening, one of said valve handles when its valve is in open position preventing the operation of said closure to expose said opening, and a float in each of said chambers having an indicator actuated thereby for indicating the quantity of water withdrawn from the chamber.

6. A tank for supplying water to a concrete mixer, provided with two chambers, and an outlet from each chamber to the concrete mixer, a valve and a handle for controlling each of said outlets, a water charging opening in the tank for supplying both of said chambers, a movable closure for said water charging opening, means for operating said closure to expose said opening, one of said valve handles when its valve is in open position preventing the operation of the closure to expose the said charging opening, and an indicator for each of said chambers for indicating the quantity of water within it.
